UNITED STATES PATENT OFFICE

153,578

DESIGN FOR A MOLDING MACHINE OR
THE LIKE

George S. Bohannon, Fort Worth, Tex.

Application April 30, 1946, Serial No. 129,132

Term of patent 7 years

(Cl. D55—1)

To all whom it may concern:

Be it known that I, George S. Bohannon, a citizen of the United States and residing in Fort Worth, in the county of Tarrant and State of Texas, have invented a new, original, and ornamental Design for a Molding Machine or the like, of which the following is a specification, reference being had to the accompanying drawings, forming a part thereof.

In the accompanying drawings:

Fig. 1 is a front perspective view of a molding machine or the like, showing my new design.

Fig. 2 is a front elevation thereof.

The rear and side not shown in the drawing are substantially plain.

I claim:

The ornamental design for a molding machine or the like, substantially as shown and described.

GEORGE S. BOHANNON.
